UNITED STATES PATENT OFFICE.

WILLIAM TURES, OF MILWAUKEE, WISCONSIN, ASSIGNOR TO REX LIGHT AND STOVE COMPANY, OF MILWAUKEE, WISCONSIN, A CORPORATION OF WISCONSIN.

HYDROCARBON-LAMP.

No. 883,152.

Specification of Letters Patent. Patented March 24, 1908.

Application filed March 25, 1907. Serial No. 364,213.

To all whom it may concern:

Be it known that I, WILLIAM TURES, a citizen of the United States, residing at Milwaukee, county of Milwaukee, and State of Wisconsin, have invented new and useful Improvements in Hydrocarbon - Lamps, of which the following is a specification.

My invention relates to improvements in hydro-carbon lamps.

10 The object of my invention is to provide for telescoping the gas conducting arm over the generator to form a heat conducting and retaining hood, as well as to secure a rigid support with minimum cost of construction.

15 Also to provide improved means for cleaning the generator nozzle, for utilizing the heat of the burner for both heating the generator and the gas conducting arm, also to improve and simplify the construction of the mixer 20 and of the auxiliary or sub-fire burner.

In the following description, reference is had to the accompanying drawings in which

Figure 1 is a side view of a lamp embodying my invention with portions partially broken away to show the oil valve and the burner. Fig. 2 is an axial sectional view of the valve, generator, and a portion of the gas tube on a large scale. Fig. 3 is a detail plan view of the cleaning apparatus for the generator nozzle. Fig. 4 is a cross sectional view drawn on line x—x of Fig. 2.

Like parts are identified by the same reference characters throughout the several views.

35 A reservoir 1 for hydro-carbon liquid is provided with a valved inlet 2 adapted to admit air under pressure to the reservoir, from the lower portion of which a tubular liquid conveying standard 3 extends upwardly to a suitable valve casing 4 provided with a valve 5 having a stem 6 and handle 7 as shown. The valve controls the flow of liquid hydro-carbon to the generator tube 10 which is supported in a substantially 40 horizontal position from the standard 3 by means of the valve casing 4 and a head piece 11. The generator tube 10 is provided with heat absorbing exterior flanges 12 formed by screw threading the tube. The tube contains suitable filtering material 13 such as wire gauze or asbestos wool. At its outer 45 end the generator is provided with a nozzle 14 which may be cleaned from time to time by a reciprocating needle 15 which extends 50 through the head piece and is provided with

a yoke 16. This yoke 16 is loosely engaged by a crank pin 17 on a wheel 18, which is mounted on a shaft 19 and rotated by means of the button handle 20. This needle therefore, has a definite field of movement, 60 and cannot be manipulated in such a manner as to injure the nozzle.

The head piece 11 is provided with a cylindrical tubular stud 21 which receives the generator tube 10, and the outer end of the 65 tube 10 is provided with a collar 22. Both the collar 22 and the tubular stud 21 are adapted to enter and fit snugly within the gas conveying tube 23 into which the generator telescopes. The tube 23 is cut out on 70 its under side between the collar 22 and stud 21 to expose the generator tube through an elongated opening 25, above a portion of which the tube 23 is perforated at 26 to provide for a slow circulation of heated air 75 around the generator tube 10 in the space between it and the remaining upper portion of the wall of the tube 23. The gas tube 23 extends outwardly from the generator and is bent downwardly and rearwardly in goose 80 neck form with the lower end elbowed and provided with a burner 27.

A collar 30 is telescoped upon the gas tube 23 and an air receiving bell 31 is provided with a hub 32 which also telescopes upon the 85 gas tube. The collar 30 is threaded and provided with a nut 35 having a conically tapered portion 36 adapted to enter the bell, and regulate the admission of air as the nut is turned to adjust it to and from the bell. 90 The gas tube 23 is apertured at 37 within the bell to admit the air to the interior of tube 23.

A sub-fire burner, comprising a tubular stem 40, flattened at its upper end and having slits 41, projects upwardly from the backwardly extending portion of the gas tube, in the direction of the generator and is adapted to permit the escape of a small quantity of gas in a thin flame elongated along the axis of the generator. By holding a lighted 100 match under the generator and near the nozzle, sufficient heat will be absorbed by it to generate a small quantity of gas near the nozzle, which gas passes downwardly in the tube in sufficient quantity to ignite at the 105 sub-fire burner, whereupon a larger quantity of gas is generated with sufficient rapidity to permit the same match to be used in lighting the main burner 27.

With the above described construction, 110

the burner 27 with the shade or globe 42 are supported from the head piece through the gas conveying tube which is merely telescoped upon the generator.

5 Having thus described my invention, what I claim as new and desire to secure by Letters Patent is.

1. In a hydro-carbon lamp, the combination of a standard provided with a suitable 10 head piece having a tubular projection, means for supplying liquid hydro-carbon thereto, a generator tube connected with said projection and arranged in communication with the hydro-carbon supply, a gas

15 tube telescoped over the generator tube and fitted to said projection and a burner supported by the gas tube substantially underneath the generator, said generator being horizontally disposed and adapted to sup-

20 port the gas tube by a detachable connection therewith, and said gas tube being out of contact with the central portion of the generator tube and apertured along its underside directly over the burner.

25 2. In a hydro-carbon lamp, the combination of a standard provided with a suitable head piece having a tubular projection and means for supplying liquid hydro-carbon thereto, a generator tube connected with and

30 arranged to receive oil from said projection, and a gas tube telescoped over the burner and provided with an elongated opening on its under side, said gas tube being curved downwardly and backwardly and provided

35 with a burner substantially underneath the generator, and said gas tube having its upper wall perforated above the burner and above said opening.

3. In a hydro-carbon lamp the combination with a suitable reservoir, of a horizontally projecting generator tube arranged in communication with the reservoir, a gas tube having one end portion telescoped over the generator tube and slidably supported at 40 the respective ends of said generator tube, and a burner connected with the other end of the gas tube, said gas tube being curved in goose neck form and arranged to support the burner underneath the generator, and said

45 50 gas tube being provided with an opening in its underside exposing the generator directly over the burner.

4. In a hydro-carbon lamp, the combination with a suitable reservoir, of a hori-

zontally projecting generator tube arranged 55 to receive liquid hydro-carbon therefrom, a gas tube having one end portion telescoped over the generator and provided with an opening along its under side exposing the generator, and a burner supported by the 60 gas tube underneath the exposed portion of the generator, said generator having a nozzle arranged to discharge into the gas tube, a cleaning needle adapted to enter the nozzle, and a crank mechanism operatively connected with the needle, and adapted to move the same a predetermined distance into and out of the nozzle.

5. In a hydro-carbon lamp, the combination with a suitable reservoir, of a horizontally projecting generator tube arranged 70 to receive liquid hydro-carbon therefrom, a gas tube having one end portion telescoped over the generator and provided with an opening along its under side exposing the 75 generator, and a burner supported by the gas tube underneath the generator, said gas tube having a collar telescoped thereon and threaded on its outer surface, an air bell having a tubular hub telescoped on the gas 80 tube, and a valve nut adjustably mounted on the collar and provided with a tapered portion adapted to enter the bell.

6. In a hydro-carbon lamp, the combination with a suitable reservoir, of a horizontally projecting generator tube arranged to receive liquid hydro-carbon therefrom, a gas tube having one end portion telescoped over the generator, and provided with an opening along its under side exposing the 90 generator, and a burner supported by the gas tube underneath the generator—said gas tube being arranged to extend outwardly, downwardly and rearwardly from the generator in a goose neck curve, together with a 95 sub-fire burner comprising a tube extending from the rearwardly extending portion of the gas tube toward the generator, with its upper end flattened and slitted to permit the escape of a small quantity of gas distributed 100 along the axis of the generator.

In testimony whereof I affix my signature in the presence of two witnesses.

WILLIAM TURES.
